UNITED STATES PATENT OFFICE.

HENRY W. HOWELL, JR., OF ELIZABETH, NEW JERSEY.

CAR-BRAKE.

SPECIFICATION forming part of Letters Patent No. 399,408, dated March 12, 1889.

Application filed February 24, 1888. Serial No. 265,202. (No model.)

To all whom it may concern:

Be it known that I, HENRY W. HOWELL, Jr., a citizen of the United States, residing in the city of Elizabeth, in the county of Union and State of New Jersey, have invented new and useful Improvements in Car-Brakes, of which the following is a specification.

This invention relates to improvements in the method of operating car-brakes simultaneously throughout an entire train consisting of a number of cars connected or coupled together in the usual manner, the brakes to be applied rapidly and equably to each car by means of cables beneath the floor of each car and connected so as to form one continuous cable to be operated by a person on the locomotive through the medium of a friction-clutch, as will be hereinafter described. It will be understood that this combination of devices is so arranged and constructed that though the brakes may be quickly and forcibly applied to arrest the momentum of a train of cars the adjustability of the method of applying the power to the cable by means of a friction-clutch is such as to relieve any undue strain or sudden shock upon the brakes and to overcome the momentum of the cars in the least possible space of time with safety thereto.

In the accompanying drawings similar letters of reference indicate corresponding parts in all of the figures.

Figure 1 in the accompanying drawings represents a car and a fragment of a car provided with my improved method of applying the brakes thereto, the bodies of the cars being in elevation, and a central section through the trucks to show more clearly the construction and operation of the brakes. Fig. 2 represents a view of a car similar to Fig. 1, showing a different arrangement of the pulleys under which the cable passes to raise the cross-bar to apply the brakes. In this arrangement the lifting-pulley is connected to the cross-bar by means of a link, *k*, as shown, the guide-pulleys *G* also being arranged differently. Fig. 3 represents plans of two trucks and the mechanism secured thereto for operating the brakes, as shown in Fig. 1. Fig. 4 represents a plan of an ordinary truck for a locomotive, upon the frame of which is mounted the mechanism by which the cable

is to be operated to apply the brakes throughout an entire train of cars simultaneously.

A in the accompanying drawings represents the bodies of two ordinary cars mounted upon trucks B of the usual construction, each truck being provided with my improved method of applying the brakes.

The brakes C are of the ordinary form of construction and are placed between the wheels of the truck and forced apart or outwardly against the tread thereof, and are supported and maintained in position by means of slotted guide-brackets F, secured to and projecting downward from the lower side or floor of the car, as shown in Figs. 1, 2, and 3, said brakes being connected in pairs by means of cross-bars D in the usual manner.

To effect a simultaneous and equable application of these brakes to a number of cars, a chain cable or wire rope, E, is provided to each car, and connected so as to form a continuous cable throughout the entire train, these cables being supported and guided by friction-rollers G, mounted upon the brackets H, secured to and extending downward from the lower side or floor of the car. On the cross-bars D, and between the friction-pulleys G, which support and guide the cable E, are placed friction-pulleys I, by which the bars D are to be raised and lowered to operate the brakes, the cable E passing over the guide-pulleys G and beneath the lifting-pulleys I, as represented in Figs. 1, 2, and 3. The brackets H and F are provided with perpendicular slots J, through which the cross-bars D pass, in order to admit of the up and down movements of the cross-bars D to apply the brakes, as shown. Guide-pulleys are provided near the ends of the car to support the cable when slack and when the brakes are not in use.

In order to apply the brakes to a number of cars simultaneously and with the required rapidity, to quickly stop a train without injury thereto, and to compensate and relieve the brakes when too much power is applied, a friction-clutch is provided, which consists of a disk, N, firmly secured to the axle of a locomotive, and a disk, M, mounted loosely upon the same axle, this disk M having a drum, O, around which the end of a cable is to be wound in applying the brakes, as shown in Fig. 4. When more power is applied to

the friction-clutch than is necessary to operate the brakes sufficiently to arrest the cars, the disks N M will simply slide over each other the same as the shoes of a brake slide over the tread of the wheels. To move this disk M longitudinally upon the axle of a truck, in order to bring the faces of the two disks N M together with sufficient force to operate the cable E throughout the entire train by their friction, a steam-cylinder, P, of the proper dimensions, is provided, to the piston-rod W of which is connected a vibrating lever, R, its opposite end forming a yoke, V, and taking into a grooved wheel, S, secured to the end of the drum O. The end of the piston-rod W is fitted with a coiled spring, T, of sufficient force to return the piston-head in the steam-cylinder P when it is required to release the friction-disk M and withdraw the brakes from the wheels.

The steam-cylinder P and mechanism to operate the friction-clutch are arranged and mounted upon the locomotive-truck in any convenient manner, the steam admitted to the cylinder, and the exhaust permitted to escape therefrom by a stop-cock on its lower side, in the usual manner, the stop-cock being closed when the piston-head has been returned by the spring T to be in readiness to apply the brakes when required.

The steam-pipe to admit the steam to the cylinder P and the stop-cock by which the exhaust-steam is permitted to escape being common devices and quite familiar to mechanicians, are not shown in the drawings.

The operation of my improved mechanism for operating car-brakes simultaneously and equally throughout a train may be briefly recapitulated as follows: The cable E, of wire or rope or chain, as preferred, passing over the friction-rollers G and beneath the lifting-pulleys I, having been connected between the several cars and attached to the cable on the locomotive-truck, one end of which being attached to the drum O, as shown, and the opposite end of the cable E made fast to the last car of the train, the system is complete and a continuous cable formed throughout

the entire train. Then, by admitting steam to the cylinder P, the loose disk M is brought instantly into contact with the disk N, secured firmly to the axle of the truck, and by their united friction the cable is wound around the drum O with sufficient force to move it the entire length of the train to operate the several brakes with equal force on each car.

It will be understood that the end of the cable being made fast to the last car, and its opposite end secured to the drum O, will be straight or nearly so when the train is in motion, as represented.

The power applied to the friction-clutch may be regulated by the admission of more or less steam into the cylinder P. In this manner the brakes are governed to meet the requirements either to stop the train quickly or gradually. When a train is to be checked and not to be brought to a full stop, the loose friction-disk M will slide over the face of the disk N, with sufficient friction only to accomplish the purpose the same as the brakes slide over the tread of the wheels.

If desired, an air-cylinder might be employed, instead of the steam-cylinder P, to operate the friction-clutch, though it is believed that a steam-cylinder would be more effective in operating the brakes throughout a train of cars composed of a large number.

Having thus fully described my invention, what I claim therein as new, and desire to secure by Letters Patent, is—

In a steam-brake for railway-cars, in combination with the friction-clutch, drum S, and cable W, extending from car to car, the steam-cylinder P, and shifting-lever R, to operate the friction-clutch to apply the brakes, and spring T, to disengage the friction-clutch to release the brakes, the stationary friction-pulleys G and movable pulley I, to operate the shoes C, and slotted bracket to support and guide the roller I in its up and down movements, substantially as herein set forth.

H. W. HOWELL, JR.
